(57) **CLAIM**

The ornamental design for a hemorrhoid treatment device, as shown and described.

DESCRIPTION

The hemorrhoid and incontinence treatment device inserts into the anus of a user. The device treats symptoms of hemorrhoids and incontinence.

FIG. 1 is a top plan view of the hemorrhoid treatment device showing my design;

FIG. 2 is a front view thereof, a back view being a mirror image thereof;

FIG. 3 is a side view thereof, an opposite side view being a mirror image thereof; and,

FIG. 4 is a bottom view thereof.
